UNITED STATES PATENT OFFICE.

GEORGE FLETCHER WRIGHT, OF WORCESTER, MASSACHUSETTS.

SHUTTLE FOR WEAVING WIRE-CLOTH.

SPECIFICATION forming part of Letters Patent No. 299,895, dated June 3, 1884.

Application filed July 10, 1883. (No model.)

To all whom it may concern:

Be it known that I, GEORGE FLETCHER WRIGHT, of the city and county of Worcester, of the Commonwealth of Massachusetts, 5 have invented a new and useful Improvement in Shuttles for Weaving Wire Cloth or Fabrics; and I do hereby declare the same to be described in the following specification and represented in the accompanying drawings, of 10 which—

Figure 1 is a front elevation, Fig. 2 a top view, and Fig. 3 a transverse section, of a shuttle embodying my invention, the nature of which is defined in the claims hereinafter 15 presented. Fig. 4 is a view of the base of the wire cop used in the said shuttle, such cop being conical in shape, or, in other words, the frustum of a cone hollow at its axis from end to end thereof.

20 The wire in being drawn off the cop unwinds from the bore, and not from the outer surface of such cop.

In my improved shuttle the cop-holding chamber is tapering, and has its axis arranged 25 at an acute angle to that of the shuttle-body; and, furthermore, there is extended from the lesser or delivery end of such chamber a curved guide for the wire to pass upon in its course to and between the delivery-rolls situated at 30 or near the middle of one side of the shuttle.

In the drawings the shuttle-body A is represented as formed of two walls, *a* and *b*, and a bottom, *c*, such walls extending upward from such bottom, at right angles to it, and at the 35 ends of the body being, with the bottom, curved, so as to form the body at each of its ends with a suitable nose, *d*. The cop-chamber shown at B is formed partly by the wall *a* and partly by a partition, *e*, extending obliquely from the 40 opposite wall, *b*, at an acute angle thereto, nearly to the wall *a*, such partition also being extended in a curved form beyond the lesser end of the chamber, so as to answer as a guide, *f*, for the wire in its passage to and between 45 the two delivery-rolls *g g*, which are intended to prevent kinking or accidental bending of the wire in passing out of the shuttle. These rolls are arranged, as represented, within the shuttle-body, and have in front of them an 50 opening or passage, *h*, in the wall *b*, such open-

ing being at or near the middle of the shuttle and for the wire to pass out of the shuttle in its flight through the shed of the warps. The bottom of the cop-chamber is that of the shuttle-body, while the rear or larger or closed end of the chamber is formed by a partition, *k*, extending across the shuttle-body from one to the other of its walls and at an obtuse angle to each of them, as represented.

This mode of constructing a shuttle or of 60 having its cop-chamber arranged within it enables the curved guide leading from such chamber to be made larger than it could be were the delivery-mouth of the cop-chamber at the axis of the shuttle. By having it larger such 65 guide works better in reducing the coils of the wire or aids to better advantage in straightening it.

Other advantages result from my improved arrangement of the cop-chamber.

I claim—

1. The shuttle-body having at or near the middle of one wall an educt, *h*, and guide-rollers *g g* arranged therein, a cop-holding chamber along the opposite wall of the body, with 75 the axis of such chamber oblique to that of the body, and a curved guide extending from the lesser end of such chamber nearly to the opposite wall of the body, such rollers and curved guide being for so directing the wire from the cop to and through the educt as to prevent kinking or accidental improper bending of such wire in passing from the cop through and out of the shuttle, substantially as set forth.

2. The shuttle having within it a cop-holding chamber formed in its body by its bottom and one of its walls, a partition extending across such body from one to the other of such walls, and another partition extending from or near one end of the first partition obliquely 90 to and across the longer axis of the body and nearly to the opposite wall, and curved, as described, an educt arranged at or near the middle of one side, and friction-rollers disposed in said educt, all being substantially as set forth. 95

GEORGE FLETCHER WRIGHT.
